L. COOK.
DEVICE FOR STROPPING SAFETY RAZORS.
APPLICATION FILED FEB. 21, 1917.

Patented Nov. 5, 1918.

UNITED STATES PATENT OFFICE.

LUMAN COOK, OF BENNINGTON, VERMONT.

DEVICE FOR STROPPING SAFETY-RAZORS.

1,284,059.

Specification of Letters Patent.

Patented Nov. 5, 1918.

Application filed February 21, 1917. Serial No. 150,262.

To all whom it may concern:

Be it known that I, LUMAN Cook, a citizen of the United States, residing at Bennington, in the county of Bennington, State 5 of Vermont, have invented a new and useful Device for Stropping Safety-Razors; and I do hereby declare the following to be a full, clear, and exact description of the invention, such as will enable others skilled 10 in the art to which it appertains to make and use the same.

This invention is a device designed for holding safety razor blades so that they may be stropped with facility.

15 Its principal object is to provide a device for performing the stropping operation that will enable both sides of the cutting edges of a safety razor blade to be stropped without the necessity of having to change the 20 blade in the holder.

Another object is to provide a simple but efficient means for attaching the blade in the holder.

A third object is to provide a pair of rolls 25 that will slide during the strokes of the stropping operation but will turn at the reversal of each stroke so as to bring the desired edge into contact with the strop.

A fourth object is to provide, in combination with the blade holder, a strop support having longitudinal tracks on which the rolls of the holder may slide.

Although but one design is shown for the purpose of setting forth this invention, the 35 invention is not to be limited to this design. The right is reserved to make any changes or alterations that practice may require, so long as such changes or alterations fall within the scope of the subjoined claims.

40 In the drawings the same numerals of reference are used to designate the same parts throughout the several figures.

Figure 1 is a perspective view of the blade holder, its containing case and its attendant strop support. This figure shows a 45 blade holder performing the stropping operation.

Fig. 2 is a plan view of the razor blade holder.

50 Fig. 3 is a section on the line 3—3 of Fig. 2.

Fig. 4 is a section on the line 4—4 of Fig. 2.

Fig. 5 is a section on the line 5—5 of Fig. 1.

Fig. 6 is a detail sectional view on line 6—6 of Fig. 1.

The holder comprises a yoke 1 and the handle 2, a rod 3 being attached at the center of the yoke and penetrating the handle. The turned ends 4 of the yoke have eyes formed in them in their ends and these eyes are adapted for pivotally engaging the studs 5 which emanate separately from and are integrally parts of the rolls 6. In alignment with the studs 5 the rolls 6 also have the apertured studs 7. On the same faces with the apertured studs the rolls 6 are provided with the pins 8. These pins are held frictionally in the rolls and are adapted 65 for sliding engagement with the slots 9 of the oscillating bar 10.

The blade support comprises the plate 11 with the cylindrical pivots 12 protruding centrally from its ends. At the front corners of the plate the round pins 13 project and these pins are adapted for sliding engagement with the slots 14 of the oscillating arms 10. The plate 11 is pivotally supported in the rolls 6 by the engagement of 75 its pivots 12 with the apertures of the studs 7.

Two headed studs 15 are affixed to the plate 11 and are designed to attach the blade 16 thereto by engaging it through its holes 17, the heads of 15 setting away from the surface of the plate 11 a distance equal to the thickness of the blade. The diameter of the heads of 15 is equal to the diameter of the holes 17 in the blade while the bodies 80 of 15 are somewhat smaller. The studs 15 can thus be made to hold blade 16 by setting it on them so that the holes 17 will drop on the edge of them, when a movement of the blade longitudinally will cause 85 the heads of 15 to engage the blade on its face. The pin 19 is fixed in the plate 11 in alignment with the studs 15 and is designed to engage one end of the blade 16 in a position to keep its face underneath 100 the heads of the studs 15, the operation of bringing the blade into this relation with

respect to the studs 15 and to the pin 19 requiring a springing of the end of the blade where it engages the pin 19. The top of the pin is beveled in the direction of the length of the plate 11 and on the side adjacent the blade 16 to facilitate attaching and detaching the latter.

The oscillating arms 10 are pivotally mounted on the studs 20 supported by the 10 arms 4 near their inner ends, the shoulder portions 21 of the studs operating as a spacing means to keep the arms in alinement with the faces of the rolls 6. Concentric with the point of oscillation the arms 15 10 are provided with slots 22 through which the studs 7 pass. These slots permit the oscillation of the arms 10.

The case 23 is designed to contain the blade holder, the recess in the upper face of 20 block 25 and in which the rod 3 rests being designed to prevent the holder from shifting therein. Cover 24 is connected to the case by the hinges 26, the strop support 27 being positioned longitudinally in the cover and 25 centrally disposed with reference to the width. Below the strop support the metallic strips 28 are secured, one on each side of the support and running the length of the cover. The strop 29 is held on top of its 30 support by having its ends engage under the yoke members 30 which have right angled bends at the ends of their legs by which they are attached (by soldering or other means) to the metallic strips 28.

35 To perform the sharpening operation the razor blade is attached to the plate 11, so that it will be held thereon by the heads of the studs 15, the end of the blade abutting the pin 19 to keep the blade in position under the heads of the studs, as previously described. The holder is then placed so that the yoke 1 straddles the strop support 27 when the rolls 6 will be in position to slide 40 on the metallic strips 28 and the blade will be above the strop.

On the forward movement the rolls 6 by contact with the metallic strip 28 will tend to turn causing the pins 8 to move upwardly carrying with them the oscillating arms 10. 50 The arms 10 by engagement with the pin 13 operate to turn the plate 11 in a direction the reverse of the direction in which the rolls 6 are moving, thus bringing one edge of the blade against the strop. When the blade 55 touches the strop further movement of rolls 6 on the oscillating arms 10 is stopped, the rolls 6 for the rest of the movement sliding along the strips 28 and the edge of the blade dragging on the strop. On the return movement the opposite edge of the blade will be 60 brought into contact with the edge of the strop as a result of reversed movements being imparted to the rolls 6 and oscillating

arms 10 by the reversal of movement imparted to the whole device.

The device may be turned over so as to sharpen edges that were previously away from the strop, the same cycle of operations being performed by the several component parts, whether the blade 16 is facing the 70 strop or whether the plate 11 faces it.

What is claimed is:

1. In a device for sharpening safety razor blades, a yoke having a handle attached thereto, rollers having integral studs for pivotally connecting them to the yoke, apertured studs integral with the inner faces of the rollers, a plate having pins in pivotal engagement with the apertured studs, oscillating arms pivotally connected to the yoke, 75 pins on the rollers adapted to engage the oscillating arms, pins on the plate engaging the oscillating arms, and means for attaching the razor blade to the plate.

2. In a device for sharpening safety razor 85 blades, a yoke having a handle attached thereto, rollers having integral studs for pivotally connecting them to the yoke, apertured studs integral with the inner faces of the rollers, a plate having pins in pivotal engagement with the apertured studs, oscillating arms pivotally connected to the yoke and having curved slots which permit the arms to move without interference from the apertured studs and further having straight 90 slots projecting substantially at right angles to the curved slots, pins on the rollers adapted to engage the straight slots on one side of the curved slots, pins on the plate adapted to engage the straight slots on the other 95 sides of the curved slots, and means for attaching the razor blade to the plate.

3. The combination with a U-shaped yoke, of a handle connected thereto, a pair of rollers having studs on the outer faces and being 100 arranged whereby the studs are axially alined, said studs being axially mounted in bearings of the end portions of the arms of the yoke, the inner faces of the rollers having studs axially arranged with each other 105 and the first studs, the studs of the inner faces of the rollers having depression bearings, a plate provided with axially alined pins on its opposite ends mounted in the depression bearings, oscillatory elements pivotally mounted on the inner faces of the arms of the yoke, each of said elements having a longitudinally extending elongated slot, and a transversely arranged elongated slot at right angles to the first slot for the 110 reception of the studs of the inner faces of the rollers, the opposite ends of the plate adjacent its corners having axially alined pins to engage the lower ends of the longitudinally extending slots, the inner faces of the 115 rollers having eccentrically mounted pins 120

engaging the upper ends of the longitudinally extending slots, whereby, as the yoke is reciprocated along a stropping device, an intermittent oscillatory movement will be imparted to the plate, and means for attaching a razor blade to said plate.

5 In testimony whereof I have signed my

name to this specification in the presence of two subscribing witnesses.

LUMAN COOK.
